UNITED STATES PATENT OFFICE

ADELBERT O. MÜLLER, OF FREMONT, NEBRASKA.

IMPROVEMENT IN BUNG-BUSHES.

Specification forming part of Letters Patent No. 222,936, dated December 23, 1879; application filed October 30, 1879.

To all whom it may concern:

Be it known that I, ADELBERT O. MÜLLER, of Fremont, in the county of Dodge and State of Nebraska, have invented a new Improvement in Bung-Bushes, of which the following is a specification.

The object of my invention is to provide a bushing that will protect the bung-hole against charring during the operation of pitching the barrel, and which is also adapted to be tightened up as the stave shrinks, and thus prevent leakage.

The invention consists in making the bushing in two parts, with an internal and external screw-thread, to adapt them to be screwed together; also, in providing the two parts with flanges which bear against the stave around the bung-hole.

In the accompanying drawings, Figure 1 represents the inside part of the bushing. Fig. 2 is the outside part; and Fig. 3 is a cross-section of my improved bung and a longitudinal section of a portion of a stave containing the bung-hole, showing the manner of placing the bushing in the bung-hole.

Similar letters of reference indicate corresponding parts.

Referring to the drawings, the outside part, A, of the bushing is composed of a cylindrical sleeve, a, with a conoidal bore, b, and an external screw-thread, c; and from the outside end, d, of the sleeve a projects a circumferential flange, e. The inside part, B, of the bushing consists of a conoidal sleeve, f, with a cylindrical screw-threaded bore, g. On the inside end, h, of the sleeve f is a circumferential flange, i, and on the exterior surface of the sleeve f is a V-shaped feather, j, parallel to the axis of the bore g.

The manner of applying the bushing is clearly shown in Fig. 3. The part B is driven into the bung-hole C from the inside of the

barrel, cask, or keg until the flange i bears against the stave at k around the bung-hole. A V-shaped groove is made in the side of the bung-hole for the reception of the V-shaped feather j. The part A is then placed in the bung-hole from the outside, and screwed into the part B until the flange e bears upon the outside of the stave around the bung-hole, as shown.

By screwing part A in part B this latter part (which is prevented from turning in the stave by feather j) is drawn up in the bung-hole until its flange i presses against the stave so closely as to form a liquid-tight joint without the use of any packing; and when, by the shrinkage of the stave or from any cause, the bushing becomes loosened in the bung-hole, it can be quickly and efficiently tightened by screwing part A farther into B, and drawing this part farther up into the bung-hole and the flange more tightly against the stave.

In addition to the advantages in the way of tightening the bushing obtained by my invention is another advantage, arising from the protection afforded to the inside edges of the bung-hole by the flange i against charring when the barrel, keg, or cask is being pitched.

Having thus described my invention, what I claim as new, and desire to secure by Letters Patent, is—

As an improvement in bushings for bung-holes, the exteriorly-cylindrical screw-threaded part A, provided with flange e, in combination with the exteriorly-conoidal part B, provided with an internal screw-thread, flange i, and V-shaped feather j, as and for the purpose substantially as described.

ADELBERT OSWALD MÜLLER.
